US0D1099064S

(12) **United States Design Patent** (10) **Patent No.:** **US D1,099,064 S**
(45) **Date of Patent:** **** Oct. 21, 2025**

(54) **WIRELESS COMMUNICATION DEVICE**

(71) Applicant: **Harman International Industries, Incorporated**, Northridge, CA (US)

(72) Inventor: **Laurent Lindenberger**, Shenzhen (CN)

(73) Assignee: **Harman International Industries, Incorporated**, Northridge, CA (US)

(*) Notice: Patent file contains an affidavit/declaration under 37 CFR 1.130(b).

(**) Term: **15 Years**

(21) Appl. No.: **29/867,435**

(22) Filed: **Oct. 25, 2022**

(51) LOC (15) Cl. **14-03**

(52) U.S. Cl.

USPC **D14/155**; D14/358

(58) **Field of Classification Search**

USPC D14/300, 348, 356, 357, 358, 372, 432, D14/433, 434, 439, 448, 480.1, 480.3, D14/480.5, 480.6, 480.7, 484.1, 137, 155, D14/157, 203.1, 203.3, 203.7, 217, 238.1, D14/239, 299, 115

CPC G06F 2213/3814; H04N 21/43632; G09G 2370/16

(57) **CLAIM**

The ornamental design for a wireless communication device as shown and described.

DESCRIPTION

FIG. 1 is a perspective view of a wireless communication device showing the new design;

FIG. 2 is a front elevational view thereof;

FIG. 3 is a rear elevational view thereof;

FIG. 4 is a side elevational view thereof;

FIG. 5 is an opposite side elevational view thereof;

FIG. 6 is a top view thereof; and,

FIG. 7 is a bottom view thereof.

The broken lines in the figures illustrate portions of the wireless communication device that form no part of the claimed design.

1 Claim, 7 Drawing Sheets
